UNITED STATES PATENT OFFICE

119,671

DESIGN FOR A COMBINED RACK AND CARRIER

Anthony W. Planeta, Rahway, N. J.

Application December 6, 1939, Serial No. 88,714

Term of patent 7 years

To all whom it may concern:

Be it known that I, Anthony W. Planeta, a citizen of the United States, residing at Rahway, in the county of Union and State of New Jersey, have invented a new, original, and ornamental Design for a Combined Rack and Carrier, of which the following is a specification, reference being had to the accompanying drawing, forming part thereof.

I claim:

The ornamental design for a combined rack and carrier, as shown.

ANTHONY W. PLANETA.
